UNITED STATES PATENT OFFICE

2,479,438

ARRANGEMENT FOR INCREASING THE TUNING RANGE OF INDUCTANCE TUNED RESONANCE CIRCUITS

Leonard O. Vladimir, Bridgeport, Conn., assignor to General Electric Company, a corporation of New York

Application November 12, 1947, Serial No. 785,265

2 Claims. (Cl. 250—40)

1

My invention relates to iron core tuning arrangements, and more particularly, to such arrangements as are employed for tuning resonant circuits such as those used in the local oscillator of a superheterodyne receiver. It is a primary object of my invention to provide an improved apparatus for tuning resonant circuits.

In general, a parallel resonant circuit may be tuned by varying either the capacitance or the inductance associated with such a circuit. In some applications, inductance tuning has been found superior to capacitance tuning in that more precise tracking is obtainable and objectional "howl" or "squeal" appearing in the output is eliminated. It is common practice, therefore, to employ a movable iron core co-operating with an inductive coil as means for inductance tuning of parallel resonant circuits.

In the oscillator circuit of a superheterodyne frequency modulation receiver, for example, it is desirable to employ a parallel resonant circuit which is tunable over a relatively broad band of frequencies, such as the range from 88 to 108 megacycles per second. It has been extremely difficult to achieve a sufficient variation in inductance with an iron core to permit inductance tuning over such a wide range. It is a particular object of my invention to provide means for increasing the tuning range of an inductance-tuned parallel resonant circuit.

Another object of my invention is to provide a tuning arrangement, for a parallel resonant circuit, which obtains the advantages of inductance-tuning over an increased band of frequencies.

A more specific object of my invention is to provide an iron core arrangement which may be employed in tuning the local oscillator circuit of a superheterodyne frequency modulation receiver over a frequency range of 80 to 108 megacycles per second.

The features of my invention which I believe to be novel are set forth with particularity in the appended claims. My invention itself, however, together with further objects and advantages thereof, may best be understood by reference to the following description taken in connection with the accompanying drawing, in which Fig. 1 is a schematic circuit diagram illustrating the operation of my invention; Fig. 2 is an equivalent circuit of the circuit of Fig. 1; Fig. 3 is a diagram, in schematic form, of an oscillator circuit which suitably embodies my invention; and Fig. 4 is a view of a coil which may be used in the circuit of Fig. 1. Like indicia signify like elements in the several figures.

2

Referring to Fig. 1, a parallel resonant circuit 1 is shown comprising a capacitance C_1 and an inductance L_1 . The input terminals 2, 3 are connected to a suitable source of radio frequency energy, not shown. A second inductance L_2 is wound on the same form with the inductance L_1 , and is connected in parallel with a capacitance C_2 . The inductance L_2 and capacitance C_2 constitute a second parallel resonant circuit 4 which is mutually coupled with the first resonant circuit 1. An adjustable tuning core, represented schematically at 5, serves to tune simultaneously both resonant circuits 1, 4. In addition, the mutual inductance between the two parallel resonant circuits 1, 4 is found to vary with adjustment of the iron core 5, since insertion of the core effectively decreases the reluctance and obtains increased flux linkage. It is understood, then, that the movable iron core effects simultaneous adjustments of the values of the separate inductances L_1 and L_2 , and of the mutual inductance, hereinafter designated M , between them. The second circuit 4 reflects an effective impedance Z_m , not shown, to the first circuit 1 by virtue of the mutual inductance M . The values of inductance L_2 and capacitance C_2 are so proportioned that the secondary circuit 4 always resonates at a frequency higher than the resonant frequency of the primary circuit 1. This may be accomplished, for example, by making inductances L_1 and L_2 equal, and by making capacitance C_2 somewhat less than capacitance C_1 .

Referring to Fig. 2, the circuit of Fig. 1 is shown in equivalent form in order to facilitate the analysis of the operation of my invention. The effective reflected impedance Z_m is shown in general form and in series with the inductance L_1 . The magnitude and sign of the reflected impedance Z_m is given by the relation

$$(1) \quad Z_m = - \left(\frac{j\omega M}{Z_s} \right)^2 (jX_{L_2} - jX_{C_2})$$

where j is the customary phase shift operator, M is the mutual inductance between L_1 and L_2 , ω is the angular frequency of the energy supplied to the input terminals 2, 3, and Z_s is the impedance of the secondary circuit. If a high Q obtains, the resistances involved are negligible in comparison with the reactances X_{L_2} and X_{C_2} of the coil L_2 and condenser C_2 , respectively, and

$$(2) \quad Z_s = X_s$$

where X_s is the total reactance of the secondary parallel resonant circuit.

Since the secondary circuit is designed to al-

ways resonate at a frequency f_1 greater than the resonant frequency f of the primary circuit,

$$(3) \quad X_{L_2} < X_{C_2}$$

at the primary resonant frequency f . Hence, X_s , the reactance of the series circuit combination of inductance L_2 and capacitance C_2 , is always of a capacitive nature, i. e., is always associated with a negative j operator. Thus, letting

$$(4) \quad Z_s = |X_s| = -jX_s$$

and combining with Equation 1,

$$(5) \quad Z_m = -\left(\frac{j\omega M}{Z_s}\right)^2 (-jX_s)$$

or

$$(6) \quad Z_m = \frac{j(\omega M)^2}{X_s}$$

Equation 6 shows the reflected impedance to be always inductive in nature.

It will be noted, from Expression 1, that the magnitude of the reflected impedance Z_m is directly proportional to the squares of the angular frequency ω and the mutual inductance M . As the iron core enters the tuning coil, the value of inductance L_1 increases, and the resonant angular frequency ω of the parallel circuit 1 (Fig. 1) decreases. At the same time, the mutual inductance M increases; furthermore, the rate of increase of the mutual inductance M is greater than the rate of decrease of the angular frequency ω . As a result, the quantity (ωM) , and hence the reflected impedance Z_m , increases as the iron core is inserted in the tuning coil. The net result is an effective increase in the inductance of the coil L_1 , due to the reflected impedance Z_m from the secondary circuit, which provides an increased tuning range.

In operating the circuit of Fig. 1 it was found that the frequency tuning range of a parallel circuit, such as the circuit 1 was increased more than 7% by adding a suitable secondary circuit, such as the circuit 4.

Fig. 3 is a schematic diagram of a circuit which is essentially that of a Colpitts oscillator modified to embody my invention. An electron discharge device 6, having cathode, control grid, and anode electrodes 7, 8, 9, respectively, is provided. Positive direct energizing voltage $+B$ is supplied to the anode 9, through a suitable inductance choke 11. The cathode 7 is connected to ground ($-B$) through a radio frequency choke 10. A modified form of the circuit of Fig. 1 is employed as the oscillatory circuit, terminal 2 being connected to the grid 8 of the device 6, and terminal 3 being directly connected to ground. The capacitance C_1 is divided into two series capacitances 12, 13 and the cathode 7 of the device 6 is directly connected to the junction point 14 between the capacitances 12, 13. The anode circuit is completed by means of a blocking condenser 15 connected between the anode 9 of the device 6 and ground. Another blocking condenser 16 is provided in the grid circuit in order to isolate the bias voltage developed across resistance 17 from the oscillatory circuit 1. By these means, the device 6 is made to serve as a generator of oscillatory energy, the frequency of the output being dependent on the resonant frequency of the parallel circuit 1.

In this application, the frequency output of the oscillator is variable over a certain tuning range by relative positioning of the magnetic core 5 in the form (not shown) on which both the inductances L_1 , L_2 are mounted. The use of the

secondary circuit 4 provides an increased tuning range, as set forth above.

Referring to Fig. 4, there is shown the aforementioned coil form 19 on which the inductances L_1 , L_2 are wound. The inductances coils L_1 , L_2 are most conveniently wound in a bifilar manner, the turns of the secondary coil L_2 being wound between those of the primary coil L_1 . I have found that best results are obtained when the secondary coil comprises a somewhat smaller number of turns than the primary coil. The coil construction is not critical, however, and the actual frequency range extension is determined chiefly by tracking consideration. The form 19 as shown is substantially cylindrical in form, and is provided with a longitudinal cylindrical hole 18. The magnetic core 5 formed of compressed powdered iron particles is also substantially cylindrical in shape, and is adapted to be variably positioned in the hole 18. By these means variations in the self inductances L_1 , L_2 are affected simultaneously with variations in the mutual inductance M between them, as heretofore described.

While I have shown and described a particular embodiment of my invention, it will be understood that numerous modifications and variations may be made without departing from the true spirit and scope of my invention.

What I claim as new and desire to secure by Letters Patent of the United States is:

1. In combination, a resonant circuit comprising an inductance and a capacitance connected in parallel therewith, an iron core movable within said inductance for tuning said circuit over a range of frequencies, and means for increasing the range of frequency over which said circuit is tunable comprising a second inductance coupled to said first inductance and a second capacitance connected in parallel with said second inductance, said second inductance and capacitance being tuned to a frequency greater than the frequency to which said circuit is tuned, and the resonant frequency of said second inductance and capacitance being varied with movement of said iron core.
2. In a radio receiver arranged to receive waves variable over a desired band of frequencies, a first tuned circuit comprising an inductance and a capacitance connected in parallel therewith, an iron core movable within said inductance to vary the tuning of said resonant circuit over a band of frequencies less than said desired band of frequencies, and means for increasing the band of frequencies over which said circuit is tunable comprising a second resonant circuit comprising a second inductance coupled to said first inductance and a second capacitance connected in parallel with said second inductance, said second resonant circuit being tuned to a frequency higher than the frequency of said first circuit, and the value of said second inductance being variable with movement of said iron core.
